UNITED STATES PATENT OFFICE

2,506,409

AUTOMATIC LOCKING AMMUNITION CONTAINER

Gabriel Walter Baumgart, Garden City, N. Y.,
assignor to Republic Aviation Corporation, a
corporation of Delaware

Application May 20, 1943, Serial No. 487,737

11 Claims. (Cl. 89—34)

1

This invention relates to containers or caissons, especially for aircraft ordnance and particularly to such for supplying largish cartridges to the larger-calibre aircraft cannon; and it also relates to the mode or method of using—installing or replacing—such caissons in the aircraft.

One of the general objects of the invention is to materially, and even significantly, increase the capacity of such containers, without thereby increasing the size or bulk or weight of the container—at least, not proportionately. For example, the capacity of a container constructed, according to the invention, of substantially the same size as one, which heretofore could contain only 15 of the 37 mm. cannon rounds, is hereby increased to exactly 50 rounds of these larger heavy cannon cartridges.

Another general object is to provide a container of this improved nature which, though containing more and larger cartridges than the usual aircraft ammunition container, will not be proportionately harder to handle or install in place in the aircraft; and will instead, be even easier to install, at least under certain circumstances, which circumstances will be hereinafter made manifest.

It is also an object of the invention to provide a caisson, and its concomitant structure in the ordnance carrier, which will render it possible to employ a new and improved mode of installing caissons, ammunition containers, and magazines, especially in aircraft.

A particular object of the invention is to provide a container so constructed that the weight of the cartridges in the container will be so balanced that they will, contrary to the usual practice, tend to remain in a state of stable equilibrium, and not shift about, even during installing or other handling, and regardless of the position or attitude of the box; and, withal, without necessitating any special retaining device, as for preventing the cartridges or the ammunition belt from slipping out of the container during handling.

Another particular object of the invention is to provide a container which will positively and directly assist and augment—instead of hindering, as usual—the feeding action of the power-feed means usually provided on the cannon for pulling the ammunition belt out of the container into the cannon.

It is also an object of the invention to provide a new and improved method or mode of installing or mounting aircraft caissons or containers in aircraft. Briefly, the new method contemplates

2

inserting a filled caisson or container from below a lower surface of the aircraft, through an opening therein; then engaging but one of the lower corners or edges of the container with suitable means on one side of said opening; swinging up the dangling, or freely hanging, box until its bottom face closes said opening and at the same time automatically locking the opposite lower edge of the box to the opposite side of said opening; securing the automatic locking means in position; and then securely counter-locking the box in its final position.

A noteworthy feature of this new method is that it reduces the number of operators hitherto required to install a filled ammunition container of this general kind and size—containing as it does at least 50 rounds each weighing at least two pounds—from two operators, to one operator. While obviously important at airfields, where there is usually a shortage of help, this feature becomes still more valuable in actual combat away from the airfield, especially in the case of fighter airplanes, having as they do but one occupant, who often has to remove the empty containers and replace them with full ones weighing well over 100 pounds, unaided and under fire.

The other objects of, and results achieved by, the present invention will either become apparent, or be made manifest, as this disclosure progresses.

The presently-preferred embodiment of the invention is, by way of exemplification only, described hereinafter with reference to the accompanying drawings, but it is to be understood that the invention is limited in its embodiments only by the scope of the subjoined claims. In these drawings,

Figure 1 is a fragmentary, front sectional view of a wing with the container installed vertically therein, between two ribs;

Figure 2 is a section along the vertical plane through the wing, fore-and-aft; or, on line 2—2 of Figure 1, sighting in the direction of the arrows;

Figure 3 is a substantially vertical section through the container, or along line 3—3 of Figure 2, sighting in the direction of the arrows;

Figure 4 is an enlarged, oblique section along line 4—4 of Figure 1, sighting in the direction of the arrows, and

Figure 5 is a detail section, along line 5—5 of Figure 4.

The drawings show only those parts of an aircraft structure—here a wing—that are directly concerned with the ammunition box; that is to

say, they show a substantially cubic caisson-well 30, formed between two adjacent ribs 31, 32, of said wing; a detachable door 33, closing the lower opening of said well; a pair of aligned upper fittings or brackets 35, riveted to the rib 32; an aligned pair of lower hooks 36, likewise riveted to the rib 32; an aligned pair of lower fittings or open sleeves 37, riveted to the rib 31; a pair of upper brackets 38, carried by one of the spars (not shown) of the wing so as to embrace laterally, the uppermost portion of the box 11, 12, 14; and an armor plate 39, fixedly mounted in the wing to the rear of said box. An opening 40 is provided in the rib 32 for an auxiliary feeding device 18.

The ammunition caisson, container, or box itself, shown in the drawings, comprises, among other things, spaced, parallel front and rear plates 11, 12, united by means of cross-ties 13, and a flexible belly band 14, formed of a relatively thin strip of steel attached at each end to one of the ties 13 and guided and restrained, in the form of a G, around the open periphery of the box, by the other ties, 13.

It also includes a track 16, 17, having a center line indicated as x—x, formed about two separate axes of curvature C, C1 within said box, and contains and guides a belt, 15 of cartridges, the links of said belt not being shown. This track comprises two opposed parts: a relatively narrow and deep, spiral, channel 16, formed on the inner face of the front plate 11; and a relatively wide and shallow, spiral, channel 17, formed on the inner face of the rear plate 12. The channel 16, guides the points of the shells 15, the channel 17 guides the bases thereof, and the belly band 14 guides the links (not shown) around the periphery of the box and prevents accidental uncoupling of said links.

The ends of the belly band 14 are anchored to the box respectively above and below the beginning of the track 16, 17, so as to form therewith, a feed mouth opposite an auxiliary feeding device 18 mounted on the cannon (not shown), which is fed by means of the belt 15. The lower or inner of said ends of the belly band 14 is folded around one of the cross-ties 13 so as to form a substantially horizontal projection 19, which acts as a bridge or chute operatively to connect the box to said device 18.

The arrangements above of the track 16, 17 within the box provides such a balancing of the weight of the shells 15 that there is no excessive load placed upon the feed mechanism on the cannon in drawing said shells into said cannon, except at the beginning of the feeding operation, which resistance is due principally to the relatively high frictional strain or force opposing the advance of the belt around the inner parts of the track where the radius of curvature of the track about the axes C, C1 is at the minimum. To meet and overcome this condition, a pair of power-sources or boosting devices is mounted along the axes C, C1. Each of said devices comprises a shaft 20, pivotally mounted across the box in ball bearings 21; a pair of sprocket wheels 22, fastened on said shaft 20 and projecting within the path of the shells 15; and a spring motor 23, mounted anterior to the plate 11 on a sleeve 24, coaxial with either C or C1, as desired, and screwed into said plate 11. Each spring motor in turn comprises a barrel 25 freely mounted on the corresponding shaft 20; a spiral spring 26 anchored at one end to said sleeve 24 and at its other end, to said barrel; a pair of

5 pawls 27, pivotally mounted on the front of said barrel; and a ratchet wheel 28, fastened on the shaft 26 to receive a crank or handle (not shown).

10 The arrangement of the said boosting devices with respect to the path of the belt is such that, during the filling of the box, when said motors 23, are wound up by hand, near the end of said filling operation, the boosting effect of the devices helps overcome the frictional forces opposing the advance of the belt along the track toward the dead end of said track, where said forces reach a maximum. During handling of the full box, and until the power feed operation starts, the 15 inertia of the belt 15 prevents premature dissipation of the energy stored up in the motors 23 by said hand-winding operation. At the beginning of the power feed operation, the positive pull applied by the cannon upon the belt is automatically augmented and boosted by said motors 23, which then drive the inner end of the belt 15 in the opposite direction, through the 20 sprocket wheels 22. If desired, due to the ratchet coupling-device 27, 28, the springs 26 may be wound counter-clockwise over more than the one or two turns it takes to bring the 10 first shells of the belt 15 into the position shown in Figure 3, without affecting the shafts 20—i. e., without affecting the position of the belt—by simply rotating the barrels 25 by hand—also in the counterclockwise direction—until the resistance of the springs 26 becomes excessive.

25 By virtue of the foregoing structures and arrangements, the capacity of this general type of ammunition container is increased manifold times; for instance, the capacity of the containers for the largish, rather heavy 37 mm. rounds or cartridges for an automatic 37 mm. aircraft cannon—a true “piece of ordnance”—is 30 increased by an additional 300%; or, from 15 rounds to 50 rounds. It also renders the larger number of shells easier to handle and reduces the number of operators required, from two, to one.

35 It is contemplated that the box 11, 12, 14 be inserted from below into the well 30; and it is also contemplated that it be provided with a three-point suspension system, which cooperates with said fittings 35, 37 and said hooks 36 to hold the box securely, but detachably, within said well. 40 This suspension system comprises: an aligned pair of upper shoulders 41 on the plates 11, 12, cooperating with the upper fittings 35 to hold the box down in the well; and two transverse lower support shafts 42, 43, projecting on each side of the box and cooperating with the hooks 36 and with the open sleeves 37, respectively, to hold the box up, securely but detachably, within the well. The support shaft 42 is fixed across the 45 box 11, 12, 14 and forms a trunnion 44, which can be engaged over the hooks 36 to hold the full ammunition box in the wing by one of its lower edges. Between the barrels 25, through a pair of sleeves 45 fixed on the front plate 11 (and through corresponding sleeves, fixed on the back plate 12), there may be temporarily inserted an auxiliary, U-shaped handle 46, when it is desired to swing the filled box (now freely hanging from the hooks 36), about said hooks, acting then as 50 hinges, into its operative position shown in Figures 1 and 3. This arrangement further aids in reducing the number of operators required, from two to one. The support shaft 43, on the other hand, is pivotally mounted in the box 11, 12 and projects on both sides thereof so as to form 55 60 65 70 75

a pair of grooved latching-bolts 47, which co-operate with the open sleeves 37 to lock the box automatically into operative position as soon as it reaches said position. This shaft 43 may be then secured against rotation and held in its locked angular position by means of a spring clip 48, mounted on a square portion 49 of the shaft and carrying a locking handle 50 and a locking pin 51, which cooperates with a hole 52, provided in the front fitting 37.

On the same square 49 is mounted a counter-locking cam-lock 53, which cooperates with a counter-locking prong 54, carried on the inner side of the door 33. This automatic counter-locking device both prevents closing of the door 33 when the box is unlatched or improperly bolted and maintains the box securely locked in its bolted position as long as the door remains closed.

On one of the lower cross-ties 13 is mounted a pair of snap-springs 55, each having a pointed locking pin 56 which cooperates with a circular V-groove 57, provided in the auxiliary handle 46, in order to hold said handle in its active position during the swinging of the box.

By virtue of this construction and arrangement of parts, it is rendered possible to carry out a new method of mounting or installing ammunition containers in the ordnance-carrier, or of replacing empty ones with full ones. This new method comprises: opening the closure of the container-well; taking a filled cannon-ammunition box; inserting the box in the aperture; freely-suspending one of the lower corners of the box from one side of the well; swinging the freely-hanging box upwardly into the opening and automatically lockingly engaging the opposite lower corner of the box with the opposite side of the well; securing the automatic locking means in position against accidental release; and closing the closure to thereby automatically counter-lock the box in final position.

The embodiment shown is susceptible of many refinements and modifications, all lying within the scope of the sub-joined claims. For example, the belly band—serving both as link-guide, and restrainer and as walls—is adapted to be replaced by rigid, permanent end-walls; and the plates by a bottom and a cover, this arrangement thus closing the box completely, except for an upper feed-mouth provided at the exit of the track. If desired, only a single booster may be employed and this single booster then arranged near the dead end of the track, about either of the axes C, C!. Also, if desired, a pair of separate, identical hand levers may be employed instead of the U-shaped handle. The door 33 may be dispensed with, if desired, and the box then provided with a solid bottom lying flush with the lower skin of the wing and acting by itself as a door to close the ammunition well 30 in the nested position of the box. Instead of the particular spring motors 23 shown, there may be employed, simplified spring motors, in which the ratchet coupling devices 27, 28 and the fixed sleeves 24 are dispensed with, the barrels 25 then being fixed to the plate 11 and the springs 26 attached to the shafts 20 and to said fixed barrels, respectively.

Having thus disclosed the inventive concepts and at least one mode of embodying them forth, what is claimed as new and inventive, is:

1. The combination with an aircraft component having an open ammunition well therein, of spaced supporting hooks at one side of said well and opening inwardly of the component, an

ammunition magazine, aligned trunnions projecting laterally from one end of said magazine arranged and organized for reception in the supporting hooks aforesaid, locking and supporting hooks opposed to and in substantial alignment with said supporting hooks and fixedly secured to the aircraft structure, and latching bolts aligned transversely of and projecting from the free end of said magazine in opposition to said trunnions and rotatable in unison by their coaction with said locking and supporting hooks for automatic locking engagement therewith upon the swinging of the magazine into the well about the supporting hooks as a pivot.

2. The combination with an aircraft structure having an open ammunition well therein, of spaced supporting hooks at one side of said well secured to and opening inwardly of the aircraft structure, spaced supporting and locking hooks on the opposite side of said well secured to and opening outwardly of said aircraft structure, an ammunition magazine having outstanding transversely aligned trunnions at one end thereof for reception in the supporting hooks opening inwardly of the aircraft structure whereby the magazine may swing into the ammunition well about said supporting hooks as a pivot, locking bolts aligned transversely of and projecting from the end of the ammunition magazine opposed to said trunnions for cooperation with said locking hooks, means whereby said bolts may be rotated in unison, and means embodied in each bolt to automatically rotate the bolts on contact thereof with the locking hooks to cause said bolts to enter and be interlockingly engaged by said locking hooks.

25. The combination with an aircraft structure having an open ammunition well therein, of spaced supporting hooks at one side of said well secured to and opening inwardly of the aircraft structure, spaced supporting and locking hooks on the opposite side of said well secured to and opening outwardly of said aircraft structure, an ammunition magazine having outstanding trunnions at one of its ends for cooperation with the supporting hooks opening inwardly of the aircraft structure whereby the magazine may swing into the ammunition well about said supporting hooks as a pivot, locking bolts aligned transversely of and projecting from the end of the ammunition magazine opposed to said trunnions, each locking bolt being substantially U-shaped in section, said section being positioned to open inwardly of the aircraft structure in opposition to said outwardly open supporting and locking hooks as the ammunition magazine swings about said trunnions to be located within the ammunition well, and means whereby said bolts automatically rotate in unison upon contact with the outwardly opening supporting and locking hooks aforesaid to become housed and engaged within the latter.

30. The combination with an aircraft structure having an open ammunition well therein, of spaced supporting hooks at one side of said well secured to and opening inwardly of the aircraft structure, spaced supporting and locking hooks on the opposite side of said well secured to and opening outwardly of said aircraft structure, an ammunition magazine having outstanding trunnions at one of its ends for cooperation with the supporting hooks opening inwardly of the aircraft structure whereby the magazine may swing into the ammunition well about said supporting hooks as a pivot, locking bolts aligned transversely of and projecting from the end of the ammunition magazine opposed to said trunnions, each locking bolt being substantially U-shaped in section, said section being positioned to open inwardly of the aircraft structure in opposition to said outwardly open supporting and locking hooks as the ammunition magazine swings about said trunnions to be located within the ammunition well, and means whereby said bolts automatically rotate in unison upon contact with the outwardly opening supporting and locking hooks aforesaid to become housed and engaged within the latter.

35. The combination with an aircraft wing, having ribs defining an open well in the under surface of the wing, of an ammunition container to be inserted in said well, a pair of supporting hooks attached to one of said ribs and opening inwardly of the wing, trunnions carried by said container to be detachably engaged by said hooks whereby the container may swing upwardly into said well, projections on said container disposed above said trunnions, and fittings fixedly secured to the rib carrying said hooks to receive said projections and thereby hold said trunnions in

cooperative engagement by said hooks when the container is positioned within the well.

5. The combination with an aircraft wing having ribs defining an open well in the under surface of the wing, of an ammunition container to be inserted in said well, a pair of supporting hooks attached to one of said ribs and opening inwardly of the wing, trunnions carried by said container to be detachably engaged by said hooks whereby the container may swing upwardly into said well, projections on said container disposed above said trunnions, fittings fixedly secured to the rib carrying said hooks to receive said projections and thereby hold said trunnions in cooperative engagement by said hooks when the container is positioned within the well, and means coacting with that end of the container opposed to the trunnions aforesaid to automatically lock the container within said well and to a wing rib with the projections and fittings cooperating as aforesaid.

6. The combination with an aircraft wing having adjacent ribs defining an open well, of hooks, opening outwardly of the wing, attached to the lower edge of the rib at one side of the well, hooks, opening outwardly of the wing, attached to the lower edge of the rib at the opposite side of said well, an ammunition box, trunnions at one end of said box to be seated in said inwardly open hooks, a projection on said box above said trunnions, a socketed fitting fixed to the rib above said inwardly open hooks to receive said projection upon the swinging of the box into the well about said trunnions and thereby hold said trunnions seated in said hooks, and means at the free end of the box for coaction with the outwardly open hooks to lock that side of the box to the rib carrying the said outwardly open hooks.

7. The combination with an aircraft wing having adjacent ribs defining an open well, of hooks attached to the lower edge portion of the rib at one side of the well and opening inwardly of the well, hooks attached to the lower edge portion of the rib at the opposite side of said well and opening outwardly of the well, an ammunition box, trunnions at one end of said box to be seated in said inwardly open hooks, a projection on said box above said trunnions, a socketed fitting fixed to the rib above said inwardly open hooks to receive said projection when the box swings into the well about said trunnions as pivots and thereby hold the trunnions seated in said hooks coacting therewith, a rotary shaft mounted at the free end of the box, and locking bolts fixed to the ends of said shaft and projecting beyond the walls of the box, said bolts having longitudinal grooves therein to cooperate with the outwardly open hooks aforesaid to automatically rotate said shaft and bolts to seat the latter within said hooks and thereby lock that end of the box to the rib carrying said outwardly open hooks.

8. The combination with an aircraft wing having a pair of spaced ribs therein defining an ammunition well and an opening in its under surface giving access to said well, of a pair of aligned hooks fixed to a rib at one side of the opening, a corresponding pair of open sleeves secured to the rib at the opposed side of the opening, an ammunition box to be received in said well, a pair of trunnions at one end of said box for reception in said hooks to swingingly mount the box thereon, a transverse shaft rotatably mounted at the free end of the ammu-

nition box and projecting at its ends on both sides thereof, grooved latching bolts fixed to the projecting ends of said shaft and arranged to lockingly coact with said open sleeves as the box swings about the hooks into the ammunition well, means for securing the shaft against rotating upon the locking coaction of the latching bolts and open sleeves, a door to be seated in the aforesaid access opening when the box is situated within the well, and means arranged to prevent the seating of said door to close the access opening prior to full locking coaction between said sleeves and latching bolts.

9. The combination with an aircraft wing having a pair of spaced ribs therein defining an ammunition well and an opening in its under surface giving access to said well, of a pair of aligned hooks fixed to one of said ribs at one side of the opening, a corresponding pair of open sleeves fixed to the other of said ribs and at the opposite side of the opening, an ammunition box to be received in said well, a pair of outstanding trunnions at one end of box for reception in said hooks to swingably mount the box thereon, a transverse shaft rotatably mounted at the end of the box in opposition to said trunnions and projecting at its ends upon both sides of said box, longitudinally grooved latching bolts fixed to the ends of said shaft and organized and arranged to receive one side of the open sleeves in the grooves thereof as the box swings about the hooks into the ammunition well, whereby the shaft and latching bolts rotate in unison to completely seat the bolts within the open sleeves aforesaid, a spring clip fixed to said shaft for rotation therewith to lockingly engage the adjacent sleeve when the latching bolts attain full locking cooperation with the sleeves as aforesaid, a cam fixed to said shaft for rotation therewith having a high point to be directed outwardly of the well when said sleeves and latching bolts are in full locking cooperation, a door to be seated in the aforesaid access opening after the positioning of the box within the well, and an arm fixed to said door to project within the well upon the full seating of the door and having its inner end recessed to conform to and receive the high point of the aforesaid cam.

10. The combination with a hollow aircraft component embodying a plurality of ribs defining a well in said component, of an ammunition box, means for hinging one end of said box to one of said ribs, and means for automatically locking the opposite end of said box to another of said ribs consisting of an open sleeve fixed to the rib to open outwardly of said well, and a rotary bolt carried by the box, the bolt and sleeve having coacting curved surfaces so organized and arranged that contact between them causes the bolt to rotate and thereby become housed and retained within the sleeve as the box swings into the well aforesaid.

11. The combination with a hollow aircraft component embodying a plurality of ribs defining a well in said component, of an ammunition box, means for hinging one of the ends of said box to one of said ribs, and means for automatically locking the opposite end of said box to another of said ribs consisting of a rotary bolt carried by the box having a groove therein opening inwardly of the well when the bolt is inactive, and a hollow open sleeve attached to the rib with its opening facing outwardly of the well, the opening in the sleeve being of less width than the diameter of the bolt, said bolt and sleeve

being so organized and arranged that as the box swings into the well one side of the sleeve is engaged in the groove of the bolt whereby the bolt rotates to reverse its position and become housed and retained within the sleeve.
